UNITED STATES PATENT OFFICE

FRANK H. ARMSTRONG, OF CHICAGO, ILLINOIS, ASSIGNOR TO SAFETY MINING COMPANY, OF CHICAGO, ILLINOIS, A CORPORATION

SELF-RETAINING CARTRIDGE

Application filed April 24, 1929. Serial No. 357,653.

The present invention relates to blasting cartridges of that type which usually comprise a rigid metallic container having a discharge opening normally obstructed by a venting means in the form of a valve, rupturable disc, or the like. This type of cartridge is preferably, although not necessarily, used in connection with blasting charges of a liquefied gas such, for example, as carbon dioxide. A suitable cap is provided for securing the venting device or rupturable disc against the discharge end of the cartridge and such cap usually comprises a chamber for receiving the released charge and a plurality of ports for directing the charge outwardly of the cartridge. In cartridges using a liquefied gas as the blasting medium, a suitable heating means is provided for reconverting the charge to the gaseous state after the cartridge has been placed in the position in which it is to be discharged, thus greatly increasing the internal pressure of the cartridge and causing the venting means to operate and release the charge into the material to be blasted. A cartridge of this general type is shown in the patent to Dent Ferrell and Arthur W. Helmholtz, issued May 19, 1931, as Patent No. 1,805,541, entitled Blasting cartridges. For a more detailed explanation of the structure and use of this type of cartridge, reference may be had to this application.

In blasting with cartridges of this type, it is customary to drill a hole, commonly known as a shot hole or drill hole, in the material which is to be blasted, such hole being of suitable diameter to receive the blasting cartridge. The cartridge after being charged, is adapted to be inserted in the drill hole, pushed back to the remote end thereof and the hole is thereafter filled and tamped to firmly confine the cartridge and the charge liberated thereby to the remote end of the drill hole. However, it has been found in practice that the filling and tamping of the

drill hole as ordinarily practiced is not a dependable means for retaining the cartridge in the desired position at the remote end of the hole.

For some reason, it seems that the tamping is in some instances incapable of holding the cartridge in place, and when such an instance arises, the cartridge, together with the tamping material is blown entirely out of the drill hole, thus giving rise to the possibility of injury to either life or property and greatly diminishing the effect of the discharge upon the material to be blasted. The logical explanation for this action seems to be that the released gases find their way between the end of the cartridge and the remote end of the drill hole and thus react upon the cartridge in a manner to force the same in an axial direction through the hole. This action is probably similar to that of a compressed gas introduced between the end of a piston and the head of a cylinder.

In view of these practical difficulties, it is apparent that some means for positively holding the cartridge in position within the drill hole is to be desired. Accordingly it is an object of my invention to provide such a means.

More particularly, it is an object of my invention to provide a holding means which is directly associated with and carried by the cartridge.

Another object of my invention is to provide a cartridge containing means capable of acting with a force substantially commensurate with the force of discharge of the cartridge.

A further object of my invention is to provide a discharge cap having mechanical means therein which are rendered operative by the discharge of the cartridge for retaining the same in the drill hole.

Specifically, it is an object of the invention to provide a plurality of gripping dogs or anchors which are capable of being projected outwardly into engagement with the wall of

the drill hole by and in proportion to the force of the discharge.

Other objects and advantages of the present invention will appear in connection with the description of the drawing, wherein,

Fig. 1 is a view in side elevation and partly in section of a blasting cartridge embodying my invention,

Fig. 2 is a top plan view of a portion of the discharge cap shown in Figure 1,

Fig. 3 is a transverse section taken on line 3—3 of Figure 1,

Fig. 4 is a transverse section taken on line 4—4 of Figure 1.

15 The cartridge retaining means of the present invention is in the nature of an improvement upon the invention of David Hodge shown in pending application, Serial No. 355,279, filed April 15, 1929 and entitled Self retaining cartridge.

Referring to Figure 1 it will be noted that the cartridge comprises a casing or container 1, having an internal charge receiving chamber 2 and a reduced neck portion 3 surrounding the discharge opening 4. A cap 5 is adapted to be fitted over the reduced portion 3 of the container and this cap is provided with an annular recess 6 wherein is located a hardened steel ring 8. The cap is provided 30 with an inwardly extending radial shoulder 7 for axially confining the ring 8. Interposed between this ring and the adjacent end of the reduced portion 3 of the container is a disc 9 of relatively mild steel which is adapted to give way or be ruptured when a predetermined pressure is reached within the container. In this connection, it is noted that the hardened steel ring 8 serves as a shear ring for the disc 9 to determine the line of breakage thereof. For the purpose of providing an effective seal between the rupturable disc and the end of the container, the latter is provided 40 with a knife edge sealing ring 10, which is preferably of relatively hard material so that it may be impressed into the disc 9. This sealing ring is preferably formed eccentrically with respect to the axis of the container so that relative rotation of the disc 9 and the container will be effectively prevented.

50 The discharge cap 5 is provided internally with a chamber 11 which is adapted to receive the charge released from the container. A plurality of discharge ports 12 and 14 radiate from the chamber 11 and serve to direct the 55 liberated charge in a direction substantially transverse to the axis of the cartridge and of the drill hole. The cap is further provided with an axial opening 15 which is adapted to receive a suitable tool for the purpose of dislodging any obstruction which might occur in the chamber 11 of the cap.

The construction thus far described forms no part of the present invention except insofar as it cooperates with elements hereinafter described.

The end of cap 5 is provided with parallel bores 16 as shown in and fitted within each of the spaced bushings 17. These are adapted to have a tight fit within the bores and are preferably Each pair of bushings 17 is transverse pivot pin 18 and whereon the anchoring elements These pivot pins are preferably provided in the bores of the bushings so as to have a fit therein. Positioned on the pivot pins 18 and 19 and intermediate the bushings 17 are the anchor elements 20 and 21 respectively. These are in the form of dogs which have ends adapted to engage the pivot pins. The anchoring elements preferably have a loose fit about the pivot pins in order that any strain be imposed upon these elements may be imparted to the pivot pins. The anchoring elements are provided with cylindrical hub portions, these are adapted to have bearing surfaces corresponding to the surfaces of the discharge cap in order that a strain may be imposed upon the anchor elements by the cap.

It will be observed by referring to Figure 1 that one pair of ports lead into the central chamber 11 in the cap are of rectangular cross section. The discharge ports merge into the body of the discharge cap in order to accommodate moving anchoring elements. Thus, it will be seen that the anchoring elements are carried from the full line position shown in Figure 1 wherein they substantially extend from the discharge ports 14 to the dotted line of Figure 1 wherein they are carried beyond the surface of the discharge cap and into anchoring positions. It will be seen that the movement of the anchoring elements is definitely limited in that the shoulders 22 and 23 are fixed relative to the discharge cap. The shoulder 22 limits the inward movement of the anchoring elements and for this purpose cooperates with the inwardly formed shoulder 24. The limiting surfaces 22 and 24 serve the purpose of providing a substantial portion of the anchoring elements in withstanding the strain thereon.

For the purpose of retaining the anchoring elements in retracted positions, the discharge cap is provided with a groove 25 which circumscircles the plane of the discharge ports. The groove 25 may be wrapped around the discharge cap in this groove for the purpose of preventing the outward movement of the anchoring elements.

In the use of cartridges of this type it is customary to insert the discharge end of the same first into the drill hole and to then push the cartridge back to the remote end of the hole to be discharged. It will be observed that the movement of the cartridge toward the remote end of the hole is such as to tend to retain the anchoring elements in restricted position. It will be understood, of course, that when the cartridge is discharged the tendency of the discharge is to force the cartridge in the opposite direction from which it has been introduced. At the time of discharge the expanded gas is liberated by the rupturing of the disc 9 into the chamber 11 of the discharge cap and with great force seek to escape through the four radial discharge ports therein. The ports 12 are substantially unobstructed and a considerable portion of the liberated gas passes outwardly through these ports. However, the ports 14 are obstructed by means of the anchoring elements, but these are substantially instantaneously moved outwardly by the force of the discharge, thus permitting the escape of the gases through all four of the discharge ports, while at the same time serving to move the anchoring elements into active position. Once these elements have been forced into the walls of the hole. The result is that the cartridge in an axial direction serves to further embed the anchoring elements in the walls of the hole. The result is that the cartridge is firmly anchored to the material to be blasted and that it remains in position with respect to the material so that the most effective results are produced. In practice, it has been found that a self anchoring cartridge of this type will usually be found with the material which has fallen as a result of the blast and in the immediate vicinity of that portion of the material to which it was anchored.

It should be understood that the specific disclosure herein made is for purposes of illustration only, and that the principles of my invention may be embodied in a variety of structural forms within the spirit and scope thereof, as defined in the appended claims.

Having described my invention, what I claim is:

1. A blasting cartridge having thereon a pivoted anchor which is engageable with the wall of a shot hole to prevent flying of the cartridge when discharged, said anchor being positioned to be actuated by the gas discharged from said cartridge.

2. A blasting cartridge adapted to be positioned within a shot hole and to be discharged therein, the discharge producing a force component tending to move said cartridge axially of the shot hole, anchoring means pivotally mounted on said cartridge and means for moving said anchoring means into engagement with the wall of the shot

hole in response to the discharge of the cartridge.

3. A blasting cartridge adapted to be positioned in a shot hole and to be discharged therein, a pivoted anchor carried by said cartridge and normally disposed within the confines thereof, said anchor being projected beyond the confines of said cartridge and into engagement with the wall of the shot hole in response to the discharge of the cartridge.

4. A blasting cartridge having a discharge cap with discharge apertures therein, in combination with means disposed in one of said apertures and movable in response to pressure therein to be projected beyond the confines of the cartridge to anchor the same.

5. A blasting cartridge having a discharge cap with discharge apertures therein, a plurality of anchor members pivotally mounted on said cap and having portions thereof overlying said apertures, whereby the force of discharge through said apertures moves said anchor members outwardly.

6. A blasting cartridge comprising a container filled with a blasting charge, a rupturable wall closing said container and a discharge cap having engagement with said container for holding said rupturable wall in place, said cap having a central chamber adapted to be placed in communication with the interior of said container by the rupturing of said wall and a plurality of discharge ports in said cap extending substantially radially outward from said chamber, and a plurality of anchoring dogs pivotally mounted on said cap and each having a portion overlying one of said ports, whereby the pressure of the discharge through said ports moves said dogs outwardly into anchoring position.

7. A blasting cartridge adapted to be positioned within a shot hole and to be discharged therein, in combination with an anchor member having a hub pivotally mounted on said cartridge and cooperating supporting and bearing surfaces formed on said container and the exterior of said hub.

8. A blasting cartridge adapted to be positioned within a shot hole and to be discharged therein, said cartridge having a slot formed therein, a pivot pin secured in said cartridge and extending transversely of said slot, an anchor member having a hub loosely surrounding said pin and adapted for pivotal movement thereon, and cooperating bearing surfaces formed in said slot and on the exterior of said hub, whereby said pivot pin is relieved of substantially all strain.

9. A blasting cartridge adapted to be positioned within a shot hole and to be discharged therein, said cartridge having a slot formed therein, an anchor dog pivotally mounted in said slot and adapted to normally lie within the confines of said cartridge

and to be projected outwardly into anchoring position in response to the discharge of the cartridge, the walls of said slot being formed to limit both the inward and outward movement of said dog and to afford a strengthening support for the same when in its outward position.

10. A blasting cartridge substantially as set forth in claim 6 and wherein the said dogs act to substantially reverse the direction of flow of the discharged gas, thus producing reaction upon the cartridge tending to hold the same in the desired position.

15. Signed at Chicago, Illinois, this 20th day of April, 1929.

FRANK H. ARMSTRONG.
